UNITED STATES PATENT OFFICE.

RICHARD A. SPURGIN, OF LONDON, ENGLAND, ASSIGNOR TO THE HAMMOND
TYPEWRITER CO.

TYPE-WRITER.

1,055,679.

Specification of Letters Patent. Patented Mar. 11, 1913.

Application filed August 11, 1911. Serial No. 643,552.

To all whom it may concern:

Be it known that I, RICHARD A. SPURGIN, a subject of the King of England, and a resident of London, England, have invented 5 certain new and useful Improvements in Type-Writers, of which the following is a specification.

This invention relates to typewriters, and more particularly to reversible carriages for 10 typewriters of the Hammond type.

The Hammond typewriter by reason of the detachable shuttle renders its use applicable to many different users, and especially to different languages, since a Hammond 15 typewriter may be used in different languages which employ different types by the mere substitution of a shuttle having type thereon adapted to the use of the particular language. In the use of the Hebrew and 20 those languages that require the operation of the machine in a manner reverse to that of our language, great difficulty has been occasioned in adapting a typewriter used for, let us say, the English language to its use 25 for, let us say, the Hebrew.

The object of this invention is to provide a reversible carriage for a Hammond typewriter by the application of which to the Hammond typewriter the machine may be 30 used equally well for the English language as for the Hebrew, and whereby it may be operated in the reverse direction to which it was first operated.

For this purpose, my invention consists of 35 a reversible carriage which is adapted to be moved by the main-spring and connected with a train of gears moving it in either one or the other direction, depending upon the direction sought to be given the carriage, 40 and which is so arranged as to permit the ready shifting of the carriage so as to make it movable from one direction to the other.

In the accompanying drawings, Figure 1 is a front-view of a Hammond type-writer 45 with my improvement embodied therein, Fig. 2 is a plan-view of the same with the parts removed to show the operation of the improvements, Fig. 3 is a vertical transverse section, taken on line 3—3 of Fig. 2, with 50 the parts shown to move the carriage in direct direction, Fig. 4 is also a vertical transverse section with the parts shown adapted to move the carriage in reverse direction,

Fig. 5 is an end of the carriage, racks and roller-bearings, and Fig. 6 is a detail view 55 of the switching-pinions.

Similar letters of reference indicate corresponding parts throughout the several figures of the drawings.

Referring to the drawings, and more particularly to Fig. 1, the base-board 10 has supported thereon the main-frame 11 of the typewriter of the Hammond type, supporting a main-spring casing 20, the operation of which main-spring brings about the step-by-step movement of the carriage, as is well known. The main-frame 11 has at each end vertical supports 12 which are provided with roller-bearings, one at each end of a rotatable shaft 14 and comprising a forward 60 roller-bearing 13¹ and a rearward roller-bearing 13². Intermediate the two end roller-bearings, a third set of roller-bearings is arranged, which comprise a forward 65 roller-bearing 15¹ and a rearward roller-bearing 15². These roller-bearings are adapted to support and guide the racks which are embraced by the flanges of the roller-bearings. Two racks are provided, a vertically fixed rack 16 and a vertically 70 movable rack 17, each, however, movable horizontally and each secured to the paper-carriage frame 18, which is provided with the paper rolls 19 at the upper part thereof, the carriage frame and rolls being well 75 known in the Hammond typewriter.

The movable rack 17 is permanently fixed in position to the carriage 18 and the fixed rack 16 is relatively movable vertically in respect to the carriage 18. It is to this relatively movable feature of one rack that the reversible feature of the carriage is due. An arrangement of gears secures the putting into or out of action of one of these racks and a train of gears operated from the main-spring moves this rack and the paper carriage when the movable rack is in engagement with the gears. For this purpose the main-spring casing 20 which is a part of the regular Hammond typewriter, is provided at 80 its exterior with a gearing 21. The escape- 85 ment-wheel 22 is of the usual form and arrangement known in this style of machine and is controlled in the usual manner by detents 23 and 24. The detent 24 is operated 90 with the keys in the well known manner,

while a ratchet 31 is secured to the shaft 30 to which is also secured the escapement 22. The step-by-step movement of the escapement imparts a step-by-step movement to the ratchet and thus to the gear or main-pinion 33 and hence the carriage is moved step-by-step.

As is well known in this type of machine, when a key is struck a yoke is operated by the inner end of the key-lever and this yoke engages a lever which operates the detent whereby the hammer is caused to strike and the ratchet 31 permitted to move one space. When the keys are operated the hammer is moved and the carriage is permitted to move in a direction from left to right, one space for each operation of each key. With the movable rack engaging the main-pinion and main-spring gear, the rack and carriage supporting it are moved step-by-step. The working surface of the teeth of the gear or main-pinion 33 are on substantially the same level with the working teeth of the main-spring gear 21 so that when the fixed rack 16 is lowered from its inoperative position to its operative position, both the main-spring gear and the main-pinion are engaged by the teeth of the movable rack. The movable rack 17 is supported by means of a pivoted elbow lever 60 pivoted to the carriage at 63 at each end of the carriage, having a curved cam-slot 61 at its lower end, which slot engages a roller 64 on a guide-pin 62 on the rack. By the operation of the elbow lever, the movable rack is either raised or lowered in respect to the carriage, since by the movement of the curved slot the guide-pin and roller rides on the same and is therefore raised or lowered depending on the movement of the elbow lever 60.

When the rack is in its lowermost position it engages the main-pinion and main-spring gear, while when it is raised, it is disengaged from them. When it is desired to move the carriage in the reverse direction, the movable rack is raised and disengaged, and a train of gears for transposing the direction of movement, meshed with the main-spring gear and main-pinion and with the fixed rack of the carriage. Hereby the fixed rack with its carriage is moved and in a direction reverse to that when the carriage was moving from left to right or normally. For this purpose, a switching lever 40 is pivoted to the main-frame in a bracket 41 and has secured thereto an arm 42 which is secured to a shaft 43 which has a forward pinion 44 adapted to intermittently engage the gear of the main-spring. This shaft is moved in bearings 45 of two uprights 46 secured to the frame of the machine. The lever 40 is connected at its other end with an arm 47 like the arm 42, a shaft 48 like the rack 43, and pinions 49 and 50, like the pinions 44 and 45 and movable in bearings 51, like the

bearings 45¹ in uprights 46¹, also secured to the main shaft of the machine. Intermediate both ends of the lever 40 an arm 53 is provided which is secured to a rod 52 and which connects with one end of a pivoted locking-lever 55, pivoted at 56 to the frame of the machine and secured by a pin 58 to the rod 52. The locking-lever 55 has at its upper free end a bent-over part with a friction-roller 59 supported thereby, adapted to engage with the upper part of the movable rack 17 and engage the same so as to hold the same in its downward position during the time that the movable rack is intended to be in its operative position, namely, engaging with the main-pinion and main gear. Thus by the operation of the lever 40 by its handle 40¹ the pinions 44 and 45, and pinions 49 and 50 are shifted and at the same time the locking friction roller is brought above the movable rack and prevents the same from being raised and holds the same in position. On the rearward movement of the pinions, the forward pinions are moved out of positive engagement with the teeth of the fixed rack and on the forward movement of the pinions, the forward pinions are moved into engagement with the teeth of the fixed rack, the rearward pinions remaining in engagement with main-pinion and main-spring gear at all times, being only shifted in respect to the same but not out of engagement therewith. The main-pinion and main-spring gear rotate in one direction and any rack engaging therewith would be moved of course in a direction corresponding thereto. A pinion engaging therewith would however be moved in the opposite direction and so the shifting pinions rotate in the opposite direction. Any rack engaging with these shiftable pinions would be moved in a direction corresponding therewith, and hence, the fixed rack is movable in a direction reverse to that of the movable rack.

In order to obtain the benefit of the tension of the main-spring so as to obtain an equal force of the same when it causes the carriage to operate step-by-step in either direction, the racks and switching pinions are so arranged as to bring about the switching of the racks and the movement of the carriage from the direct to the reverse direction when the spring is partially unwound. This is brought about by causing the teeth of the fixed rack at about the central part of the same, namely when the space bar shows the position of the carriage to be about 45, to be decreased in their height to a slight extent so as to permit the ready insertion of the teeth of the pinion with the teeth of the fixed rack. Thus by this arrangement the spring acts to draw the carriage in one direction with an equal tension and then acts to draw the carriage in the opposite or reverse direction with substan-

tially the same tension, which is very advantageous for the efficient operation of the machine.

The operation of my improved device is as follows: Assuming the movable rack to be in engagement with the main-pinion and gear of the main-spring and the keys of the machine to be operated, the movable rack and the carriage supporting it will be moved in the direction usual to this type of typewriter and corresponding to the normal direction incident to the use of the English language, namely, from left to right. Then the carriage is moved to the position corresponding to the initial or zero position, which, for the embodiment shown in the drawing, corresponds to that position of the carriage when the same is at a place marked 45 on the scale-bar 19¹ and whereby the reduced teeth of the fixed rack are in alinement with the shaft having the switching-pinion thereon. The switching lever is then operated and the pinions are moved into engagement with the fixed rack supported by the carriage, and simultaneously therewith the locking friction-roller is moved out of the path of the movable rack whereby the movable rack may be raised out of engagement with the main-pinion and main-spring gear. Immediately after that the elbow-levers with the curved slots are moved, and thereby the guide-pins and rollers engaging the curved slots are caused to follow the curved slots and to be raised upwardly whereby 35 the rack to which the guide-pins are secured, is raised upwardly and out of engagement with the main-pinion and main-spring gear. The movable rack being thus out of engagement with these gears and the fixed rack 40 having been brought into engagement with the switching-pinion, which transposes the direction of movement of the main-pinion and main-spring gear, on the operation of the keys of the typewriter the fixed rack 45 will be moved in the opposite or reverse direction to that in which it moves when the movable rack engages the main-spring gear and main-pinion. The machine may then be operated in the reverse direction and becomes adaptable to uses such as make such 50 reverse direction imperative. When it is desired to again use the machine in the normal or direct direction, the elbow-levers are first operated, and thereby the movable rack 55 is brought into engagement with the main-spring and main-spring gear and the friction roller moved so as to embrace or lock the movable rack in engagement with the said main-spring gear and main-pinion, and 60 thereafter the switching lever is operated to move the forward pinion out of engagement with the fixed rack. The operation of the keys of the machine will then move the carriage in the normal direction. It will be 65 noted that it is essential that when trans-

posing from the direct direction to the reverse direction, the pinion must first engage the fixed rack and then the release of the movable rack be effected, while when transposing from the reverse direction to the normal direction, it is necessary to engage the movable rack with its operating gears before the pinions are disengaged from the fixed rack. In order to obtain the benefit of the equal tension of the spring in either 70 direction, it is essential that the transposition be made when the carriage is in a position corresponding to that position where the pinions are in alinement with that portion of the fixed rack where the teeth have been smoothed off slightly so as to permit the ready insertion of the teeth of the pinion 75 into the teeth of the rack.

I have shown an embodiment of my invention, but it is clear that changes may be 80 made therein without departing from the spirit of the same, since my invention consists in having a fixed and a movable rack on the carriage of a Hammond typewriter, and placing into operative position with the 85 main-spring either one of these racks, by means of which and by transmission gears, the carriage is moved in either one or the other direction, and more particularly in the arrangement of the parts described and 90 operated by the switching lever which imparts to the invention a practical operation and a ready application of the invention to the Hammond typewriter.

Having thus described my invention, I 100 claim as new and desire to secure by Letters Patent:

1. In a typewriter having a carriage, the combination of a vertically fixed and a vertically movable rack on the carriage, a main-spring, means interposed between the main-spring and the racks for moving one rack 105 horizontally in one direction, and the other rack horizontally in the other direction.

2. The combination of a main-spring gear, 110 a vertically movable rack adapted to be engaged by the main-spring gear, and to be horizontally moved thereby in one direction, and a vertically fixed rack adapted to be horizontally moved by the main-spring gear 115 in the other direction, when the vertically movable rack is out of engagement with the main-spring gear.

3. In a typewriter, the combination of a main-pinion, a main-spring gear, means for 120 moving both step-by-step, gears adapted to engage the main-spring gear and main-pinion, gears movable with said engaging gears, a vertically fixed rack, a vertically movable rack, means for moving the movable rack 125 into or out of engagement with the main-spring gear and main-pinion, and a lever for moving the gears engaging the main-spring gear and main pinion.

4. In a typewriter, the combination of a 130

vertically movable rack, pins on said rack, pivoted arms having curved slots engaged by the pins, said arms being adapted to raise or lower the movable rack.

5. In a typewriter, the combination of a main pinion, a main-spring gear, means for moving both step-by-step, gears adapted to engage the main-spring gear and main pinion shafts for said gears, additional gears for said shafts, a vertically fixed and a vertically movable rack, means for moving the movable rack into or out of engagement

with the main-spring gear, and main pinion, and levers for moving the gear shaft for moving the gears engaging the main-spring gear and main pinion into or out of engagement with the fixed rack. 15

In testimony, that I claim the foregoing as my invention, I have signed my name in presence of two subscribing witnesses.

RICHARD A. SPURGIN.
